(57) **CLAIM**

The ornamental design for a clutch transfer device, as shown and described.

DESCRIPTION

FIG. 1 is a perspective view of a clutch transfer device illustrating our new design;

FIG. 2 is a top plan view thereof;

FIG. 3 is a front elevational view thereof;

FIG. 4 is a left side elevational view thereof; and,

FIG. 5 is a bottom plan view thereof.

The broken line showing is for illustrative purposes only and forms no part of the claimed design.
